[57] CLAIM

The ornamental design for a color video printer, as shown and described.

DESCRIPTION

FIG. 1 is a top, front and right side perspective view of a color video printer showing my new design;
FIG. 2 is another perspective view thereof, showing the cover in an open position;
FIG. 3 is a top plan view thereof;
FIG. 4 is a front elevational view thereof;
FIG. 5 is a bottom plan view thereof;
FIG. 6 is a rear elevational view thereof;
FIG. 7 is a right side elevational view thereof; and,
FIG. 8 is a left side elevational view thereof.
